UNITED STATES PATENT OFFICE

2,106,604

RESISTOR

Claude A. Jagger, Schenectady, N. Y., assignor
to General Electric Company, a corporation of
New York

Application March 12, 1936, Serial No. 68,412

2 Claims. (Cl. 201—67)

My invention relates to resistors and particularly to resistors of the type in which a resistance conductor is supported on an insulating member, the member and conductor being subsequently coated with a protective insulating material.

An insulating material commonly employed in the past for coating resistors of this type is vitreous enamel which is baked on after being applied to the resistor. Difficulty has been experienced with resistors thus coated due to the tendency of the enamel to break away at the points where the connection leads pass through it when the leads are flexed. Flexing of the leads not only has caused the enamel to break away around them but also has resulted in the breaking of the leads themselves or of some of the strands thereof, where stranded material is used, due to a repeated sharp bending of the lead over the edge of the broken enamel. It is the object of my invention to provide an improved resistor construction by which the breaking away of the insulation coating around the connection leads is avoided. By thus preventing the breaking away of the coating around the leads the leads themselves are less liable to be broken by the repeated flexing thereof.

My invention will be better understood from the following description taken in connection with the accompanying drawing, and its scope will be pointed out in the appended claims.

Referring to the drawing, Fig. 1 is a side view of a resistor illustrating an embodiment of my invention with portions of the protective coating removed, and Fig. 2 is an enlarged detail thereof.

The resistor which I have chosen to show to illustrate my invention comprises the porcelain tube 1 upon the outer surface of which is wound the resistance wire 2 in the form of a helix. At the ends of the porcelain tube are the connection leads 3 to which the two ends of the resistance wire are connected, each lead being shown as comprising a stranded cable which is passed around the tube with the ends thereof twisted together. In addition to the two connection leads 3 I have shown the resistor provided with several intermediate connection leads or taps 4 which are formed in a similar manner to leads 3 and are connected with the resistance wire where the latter crosses the connection lead.

After the leads 3 and 4 are secured in place on the tube I apply to each lead a reinforcing member shown at 5. Such a member is illustrated as comprising a small metal eyelet which is threaded on the lead and is arranged with

the flange thereof toward the tube. For convenience in holding the eyelet in position on the lead until the coating is applied and becomes hard one may pinch the sides thereof against the lead. With the reinforcing member in place on each of the connection leads the entire assembly is given a coating of a suitable protective insulating material such, for example, as vitreous enamel which is represented at 6 and which after being baked forms a hard heat resisting covering. In consistency the material employed for the coating should be somewhat thick so as to completely cover not only the tube and the resistance wire but also the eyelets which, as shown in Fig. 2, thereby become firmly embedded in the material.

While I have mentioned the use of vitreous enamel as one example of a suitable material for the protective coating it will be understood that my invention is not restricted to the use of such material but is applicable to the use of a wide variety of organic or inorganic compounds and cements. Furthermore the reinforcing member 5 need not necessarily be in the form of an eyelet but may simply comprise a sleeve. Moreover it may be a split sleeve or a split eyelet which may be placed over the lead and the sides clamped together thereon.

By the use of such a reinforcing member I am able to avoid the difficulties previously experienced with the cracking off of the coating and obtain the additional benefit of lessening the liability of breaking the lead, for the same is firmly supported by the reinforcing member which is itself surrounded by and embedded in the material forming the coating. I prefer to employ an ordinary metal eyelet as the reinforcing member for such in addition to its cheapness is provided with an integral flange which by being securely embedded in the coating material firmly supports the tubular portion of the eyelet against bending forces due to a flexing of the lead which might otherwise crack the coating.

I have chosen the particular embodiment described above as illustrative of my invention and it will be apparent that various modifications may be made without departing from the spirit and scope of my invention, which modifications I aim to cover by the appended claims.

What I claim as new and desire to secure by Letters Patent of the United States is:

1. A resistor comprising an insulating member, a resistance conductor wound around said member and provided with a flexible connection lead, having a portion extending outwardly from said

member, a tubular member surrounding said portion of the lead having an annular flange adjacent said member and an enamel coating on the insulation member, the conductor and the tubular member.

5. 2. A resistor comprising an insulating member, a resistance conductor wound around said member, a flexible connection lead secured to said

conductor and having a portion extending outwardly from the member, an eyelet having an annular flange at one end thereof, said eyelet surrounding said portion of the lead with the flange thereof adjacent said insulating member and a coating of baked enamel covering said insulating member, conductor and eyelet.

5
CLAUDE A. JAGGER.
